ELECTRICAL CONDENSER AND PROCESS.

Application filed May 12, 1920, Serial No. 380,919. Renewed February 26, 1927.

This invention relates to improvements in processes and apparatus for manufacture of electrical condensers of the sheet type and more particularly of the type wherein mica is used for the dielectric sheets. The object of the invention is to obtain an improved condenser of the sheet type which comprises a stack consisting as nearly as possible of only alternately-disposed 10 sheets of mica and metal foil in permanently intimate contact with each other, the interior of the stack between the sheets being freed as nearly as possible of air, moisture and all materials other than the mica and 15 foil sheets themselves, the mica and foil sheets having nothing whatsoever between them when the object of the invention is completely attained. The foils adapted for my processes are preferably soft and non-20 resilient so that as the result of the execution of the process they are in intimate contact with the mica sheets, their surfaces inside the stack of sheets being freed of air, moisture and wax and sealed from the outside atmosphere. Therefore I prefer lead 25 foil (sometimes known as "tin-foil" in the trade), although not only may there be used soft metal foils as of copper thin enough to be sufficiently non-resilient, but the foils 30 themselves may have some degree of resilience although that is not so desirable. Owing to the soft, inert or non-resilient character of such foil sheets, they exert no tendency to force the sheets apart after they 35 have been compressed together, and the resultant condensers will consist of mica and foil sheets compressed into persistently intimate contact with each other without any substantial intervention of wax which has 40 existed between the sheets during the execution of the process of construction as an agent for washing out air and moisture from between the sheets. The condenser is permanently compressed mechanically to maintain the above condition, and to the same end is permanently embedded in a mass of suitable paraffin; the condenser prior to such embedding being subjected to the highest practicable compression, so that the treatment 45 during manufacture and the permanent compressing and embedding serve respectively to eliminate from and prevent re-entry into the interior of the stack of materials foreign to the mica and foil sheets.

The invention consists in certain of the steps of the processes described herein and in certain combinations of such steps, in the improved condenser itself, and in certain features of apparatus employed, all as will be clearly pointed out in the claims. 55

Fig. 1 is an elevation of the building stand.

Fig. 2 is a plan and Fig. 3 is an elevation of the same inserted in the building tray.

Fig. 4 is an elevation of the pressing frame.

Fig. 5 is an elevation showing the material-stack and pressing frame in dotted lines and subjected to a bath of paraffin in a container, the latter being heated. 60

Fig. 6 is an elevation showing the compression of the material-stack in the pressing frame after removal from the bath of Fig. 5. 70

Fig. 7 is an elevation of part of the material-stack which has been selected therefrom for use in or as a condenser stack. 75

Fig. 8 is an elevation of an assembled condenser stack or condenser consisting of a number of the selections of the material-stack of Fig. 7, said number being assembled, insulated from each other at their end faces and connected together in series to constitute a long well-known form of series condenser. 80

Figs. 9 and 10 are elevation and plan respectively showing the condenser stack (in dotted lines, Fig. 9) as inserted into its permanent container or casing, the condenser and casing being highly compressed together in a spring press in Fig. 9, and a temporary false head being secured to the top of the 90 casing.

Fig. 11 is a detail of the leaf spring forming a part of the press of Fig. 9.

Fig. 12 is an elevation showing a form of permanent spring clamp for the condenser. 95

Fig. 13 is a diagrammatic plan of apparatus involving a vacuum tank in which is inserted the apparatus of Fig. 9, and a wax reservoir or paraffin tank connected by pipes to the vacuum tank for the purpose of filling 100 the condenser casing with embedding paraffin.

Fig. 14 is an elevation of apparatus employed in the special process of cooling the embedding paraffin in the condenser casing.

Fig. 15 is an elevation, partly in section, of 105 the condenser casing of Fig. 10 containing the embedding and condenser, with casing cover in place.

While any kind of wax or similar material may be employed in this invention, nevertheless paraffin wax is very highly preferable as being specially adapted to the processes and product hereof. Also a small percentage (say five per cent more or less) of carnauba wax or waxes possessing similar properties is mixed with the paraffin. The addition of the carnauba wax raises the melting point 5 of the mixture and when cooled provides a harder material for the condenser embedment. This specification of wax refers to the wax used in all the steps of the processes. Wherever reference is made hereinafter to paraffin alone, it is to be understood as preferably including the small percentage of carnauba wax. The wax used in all the processes hereof is preferably previously freed from moisture as by heating it to from 100° centigrade to 180° C.

The condensers made by the processes hereof are more particularly adapted for use under conditions where it is important that there shall be minimum electrical losses in the condenser in service, as in radio telegraph transmitters or in power lines, laboratory standards and the like. The condenser stack, in any case, may be employed as a unit in any desired way, or it may be constructed in sections which may be grouped in service in any desired relation of series, parallel or series-parallel, or the condenser may be constructed into sections permanently connected in series, as in the radio telegraph transmitting use 25 where the condenser is not only constructed with sections insulated from one another at their end faces, in the well-known way, but the sections are permanently connected in series in the well-known manner via foils projecting from the stack-sides.

In preparation for the processes, the sheets of mica and foil are cut to whatever sizes may be desired for a particular design of condenser. The foil sheets being usually longer and narrower than the mica sheets as in the ordinary sheet condenser. The foil sheets are rolled to be perfectly flat, and the mica sheets are tested, dried and stored in air-tight containers to await execution of the processes.

As the first process, all the sheets, of both mica and foil, are coated with the paraffin which serves later as a detergent for washing out air and moisture from between the assembled sheets,—later steps being employed for the purpose of squeezing out this paraffin from between the sheets to the greatest possible extent with the view of leaving a condenser stack consisting only of the sheets of mica and foil, preferably freed from all the paraffin which has been temporarily employed for the purpose of washing out the other undesired foreign materials, i. e., air and moisture. This coating may be done by treating the loosely-assembled sheets to a bath of hot

paraffin, this being done preferably while the process of building up the material-stack out of the separate sheets is being effected, this preference being due to the fact that the sheets when wet with paraffin are much more conveniently held together at this stage of the processes than when dry. At this stage, the stack is called the material-stack because it constitutes the material out of which the eventual condenser stack (or simply condenser) is to be made as by selecting a sufficient length or lengths of the material-stack which has or have electrical capacity suitable for the condenser.

Fig. 1, in elevation, shows the building stand consisting of a horizontal metal plate 1, two vertical posts 2 at the rear, each of these posts being cut away at 3 to aline the mica sheets during the operation of building the material-stack, and four legs 4 are provided on the bottom 1.

Figs. 2 and 3 show the building stand of Fig. 1 inserted in a waxing tray 5, the latter being heated by a very small Bunsen burner 6 (Fig. 3) to keep simply warm the paraffin in the tray. Just before each sheet of mica or foil is placed first on top of the base 1 and then on top of one another alternately, the operator dips each such sheet in the paraffin in tray 5 and then places it on the growing stack shown in Figs. 2 and 3. As stated, the cut away portions 3 of posts 2 aline the mica sheets 7 as shown in Fig. 2. Then on top of each coated mica sheet is placed a coated foil sheet as 8, the first foil sheet being placed say so that its left projects to the left of the mica sheet 7, but at its right it does not extend to the edge of the mica sheet 7. Then another coated mica sheet is placed exactly on top of the first foil sheet 7, being alined therewith by the cut away portions 3 of the posts 2. Then the next coated foil sheet as 9 is placed on top of the last mica sheet but extending to the right beyond the mica sheet and at its left not extending to the left end of the mica sheet. As the operator puts each foil sheet in place, she can and should observe whether any air bubble is entrained in the paraffin (due possibly to incomplete dipping), and if there be, or preferably in every case, she smooths down (squeegees) each foil to squeeze out the air.

Likewise, in putting each dipped mica sheet in place, she presses it down on the coated foil sheet beneath it, for the same purpose of squeezing out air. Thus the material-stack is built up of alternated sheets of mica and foil, while the successive foil sheets are placed so as to extend respectively at opposite ends of the stack and overlap one another (although separated by a mica sheet) in the central part of the areas of the mica sheets in the stack. The bottom 1 of the building stand (Figs. 1 and 2) is set down in the body of liquid paraffin in tray 5, so that it is heated by the paraffin 130

fin therein, the legs 4 holding the bottom 1 off from the bottom of the tray 5 so that the heated paraffin can circulate freely around bottom 1. Thus, during the building operation, the material-stack under construction is kept warm, i. e., both by the warm coatings on the respective sheets and by the heat conducted from the warm paraffin in tray 5 by the metal base 1 and metal posts 2 and conducted upwardly by the growing stack itself. This maintenance of warming during building assists in keeping down unnecessary thickness of the coating paraffin between sheets (due to the increasing tendency of the growing stack to squeeze out excess paraffin by gravity) and also assists in tending to avoid the entrapping of air in the stack at this stage (due to the tendency to greater intimacy of the sheets and the consequent tendency to cause the liquid paraffin to wash out air and moisture from between the sheets rather than to permit entrance or entrapping between the sheets). If the material-stack during the building operation becomes insufficiently warm, or if it hardens as appears to the operator's eye, she may spoon up paraffin from tray 5 and pour it over the material stack from time to time for the purpose of keeping warm and soft the paraffin between the sheets.

The material-stack may be built completely under a bath of paraffin, but as described above it is usually built in atmosphere with its lower end in heat conducting relation with the paraffin in tray 5, which causes less exposure of the operator's fingers to the heated paraffin. It is immaterial that the small corners or edges of the sheets which are held in the operator's fingers during the dipping operation be not coated with the paraffin, for the dipping and building operations leave sufficient paraffin on the sheets so that in the building operation itself and especially during the subsequent squeezing or washing out operation the entire surfaces of the sheets are washed of air and moisture by the outgoing paraffin, it not being the object of the invention to retain any paraffin permanently on the sheets. The temperature of the paraffin in building tray 5 during the coating and building operation is about 70° centigrade, i. e., about the temperature the operator's fingers will conveniently stand.

During the building operation, in case the eventual condenser is to consist of a number of separate sections, temporary section separators of metal or any other desired material may be inserted as a convenient method of separating the sections in the material stack, particularly if during the building operation pains are taken to insure that each section has the same electrical capacity, as by using material of uniform thickness for the mica sheets and by inserting the temporary

separators or markers above the same number of mica sheets for each section.

After the material-stack is built to the capacity of the building stand of Figs. 1, 2 and 3, it is allowed to cool therein sufficiently to permit convenient handling without impairing the unitary character of the stack consisting of the sheets temporarily held in alignment by the paraffin coatings, and then transferred to the so-called pressing frame shown in Fig. 4. This frame consists of a substantial metal base 10 with four upright metal posts 11 at the four corners thereof. Each of the four posts 11 is provided with cut away portions 12 like the cut away portions 3 of the posts 2 of Fig. 1, to aline the four corners of the mica sheets in the stack. When the material-stack is inserted in this pressing frame, the foil sheets project out at both ends of the stack between the vertical posts 11, the cut away portions 12 of the posts 11 serving to hold all the mica sheets in alignment as stated. After the material-stack is inserted in this pressing frame, a plate 13^A with four holes for the four posts 11 is slipped down over the said posts and upon the top of the stack. On plate 13^A is placed a plate 13 between the posts 11, to serve in a later step as a temporary compressing member on the stack, co-operatively with the base 10 of the pressing frame. This plate 13 has a central depression 13^B for use in a manner to be described later.

The next step consists in inserting the pressing frame containing the material stack into a bath of hot molten paraffin in a temporary container 14 (Fig. 5). During this bath, the container is heated by the flame of an ordinary Bunsen burner 15. In this step, the paraffin coatings on the sheets which yet remain as thin layers between sheets in the material stack are completely liquefied. This heating bath is maintained for about twenty minutes, the temperature of the paraffin being at substantially 135° C. By the time the material-stack is thoroughly heated, some of the moisture remaining with the paraffin between the sheets inside the stack becomes vaporized and escapes from the stack into the bath. Such moisture is that which may have been entrapped in the coating paraffin during the dipping and building operation when the paraffin was not at so high a temperature as in this bath, i. e., being then preferably less than 100° C.

Upon completion of the treatment of the material-stack in the heating bath, it is subjected to the highest practicable mechanical compression, by some such means as that shown in Fig. 6. This is a very important step in the process. It results in substantially completing the squeezing out of the thin paraffin layers between the sheets and thereby washing out from the interior of

the material-stack most of the remaining air, moisture and any other impurities. The continued presence of any foreign matter between the sheets, even the paraffin itself, is detrimental in the service of the condenser as being a cause of electrical losses or breakdowns in service. This step may be effected by applying an ordinary large C-clamp and screwing it up by hand as tightly as possible, or by employing any other powerful press such as the common air or press. By highest practicable compression is meant the highest compression which it is practicable to obtain without injuring the soft metal foil at the temperature employed,—for this squeezing out process is most effective when executed forthwith upon the removal of the stack from the heating bath in the paraffin. The pressure usually employed is of the order of several hundreds of pounds up to say one thousand pounds per square inch of the active area of the mica sheets, i. e., that area of the mica sheets which lies between the overlapping foil sheets. Although any standard form of powerful press may be employed, yet Fig. 6 shows a practicable form which has been employed successfully. This consists simply of two or more bars 16 threaded and extending through end plates 17 and 18; and a screw 19 provided with lever-handle 20, the screw 19 passing down through a threaded opening in plate 18 and its lower end bearing in a centering hole 13^b in the plate 18. A very simple and effective alternative substitute for this apparatus, however, is the ordinary heavy C-clamp referred to above. If there be used any ordinary press or clamp, then after partial cooling and under the compressing, or at intervals before complete cooling, the press or clamp should be further tightened to compensate for the shrinkage or contraction during cooling, thereby restoring the initial high compression. Hence, it is preferable at this stage to employ some form of spring clamp such as that shown in Fig. 9, not only to avoid repeated tightening up of the clamp, but to continuously preserve the high mechanical compression at a uniform amount throughout the cooling step. The compression above described is done preferably while the stack is supported or braced laterally by means of the posts 11 of the pressing frame, thus preventing tilting of the stack or the displacement of the sheets relatively to each other during the application of pressure. The lateral bracing of the stack while under compression is very important, especially when the height of the stack exceeds the longest plane dimension of the base.

After thorough cooling of the material-stack, the press or clamp is removed; but before this removal the cooling should be complete in order that all foreign matter including air and moisture may be prevented from

re-entering the material-stack after the removal of the clamp. Under proper operation of the process and upon timely removal of the clamp, the stack will be held in its finished condition by means of the hardened 70 coating of paraffin which envelops the stack and has run in between the margins of the foil sheets which project beyond the stack of mica sheets; so that all the sheets will be held together in the intimate contact which 75 was produced by the application of the compression. In other words, at this stage, after the cooling and upon the removal of the clamp, the material-stack is hermetically sealed by the enveloping paraffin sheath 80 which includes the paraffin existing between the margins of the successive mica and projecting foil sheets, all of which paraffin may be called the marginal paraffin. This hermetical sealing by the marginal paraffin 85 serves to bind the sheets together and maintain when cooled the condition of high compression initiated by the press, due to the facts that no air can enter between the sheets to force the sheets apart, and that the lead 90 foil sheets are inert or non-resilient and exert no tendency to force the sheets apart. Thus after the removal of the clamp from the thoroughly cooled stack, the condition of high compression which has resulted in the extremely intimate contact of the mica and foil sheets is preserved notwithstanding the removal of the clamp. Thus said desired condition of the material-stack is fully maintained independently of the degree of success 95 attendant upon the process of squeezing out the paraffin from between the sheets to the greatest possible extent; and no reliance is placed or required to be placed upon any such remaining paraffin for the purpose of 100 holding the material-stack in this condition; the object of the process being, for the greatest good of the condenser, to remove all the paraffin from between the sheets.

At this point, selection is made from this material-stack of that portion or those portions which may be desired for the condenser stack or condenser itself. In case temporary markers have been employed, the stack is simply divided at such markers. If no markers have been used, great care is necessary in splitting off the desired portions from the material-stack in order not to disturb the air-tight highly compressed condition of such portions; and this is done with the aid of a thin knife carefully applied and inserted in order to split off the desired portions. If it is desired to produce a sectional condenser, sections of approximately the desired capacity 115 may be split off from the material-stack. If 120 the condenser is not to be a sectional condenser but is simply to consist of a single section, then a single portion is split off or the entire material-stack may be used. A section for a sectional condenser is shown in 125 130

Fig. 7 where 21 and 22 indicate the respective bunches of foil ends at the opposite ends of the section and projecting from between the mica stack 7, each bunch of foil sheets being 5 soldered together.

In Fig. 8 is shown the next step wherein are assembled the sections into which the material-stack has been divided, this assembly being particularly adapted for a sectional 10 condenser. The single section of Fig. 7, however, may be permanently clamped and used as a complete condenser, for its air-tight condition with mica and foil sheets closely compressed together adapts it for such final 15 use. In the assembly of Fig. 8 are provided insulating barriers or separators 23 between the sections. These may be mica sheets. In case temporary markers have been used for the sections in building the material-stack, 20 these insulators 23 simply replace such markers. In the assembly of Fig. 8 also, the sections are electrically connected together by connections 24, in the manner long practiced for producing a sectional condenser (as 25 shown), and, of course, as usual, the separators 23 project only at one end of the condenser where the sections are at different potentials and require insulation from one another and where there are no connections between the sections. In practice, these connections 30 24 are constituted simply by soldering together adjacent bunches of foil ends. At this point, if my processes have been carefully followed, the condition of each section 35 will be the same as the condition of the completed material-stack, i. e., each section is in such condition that it might be used alone as a condenser. The subsequent treatment of the assembled sectional condenser of Fig. 8 40 (to be described in connection with Figs. 9 and 10) is that simply which is desirable to put the assembly into the same said condition as is each section and also to insure the maintenance of such condition as by a permanent 45 embedding in paraffin.

In Figs. 9 and 10 (elevation and plan respectively) is shown part of the apparatus for such further treatment, and in Fig. 11 is shown a detail of the leaf spring employed.

In Figs. 9 and 10, the condenser stack 25, shown in dotted lines in Fig. 9, has been inserted in its final metal casing 26. At this stage, the condenser has placed on its top its final stud plate 27, (Fig. 8), with high potential terminal or stud 28 mounted therewith and projecting upwardly, and conducting strip leads 41 connected to the foil-bunches of opposite potential stack-sections as in Figs. 12 and 15. On top of the casing 26 is secured 50 by screws a temporary head 29, provided with a cross piece 30, (Fig. 10) having a central opening up through which projects the stud terminal 28. This serves to center the condenser 25 in its casing 26; and this 55 temporary head 29 serves to receive the par-

affin which is afterwards filled in around the condenser in its casing. The entire casing 26 is mounted in the press shown in Fig. 9, said press consisting of top and bottom plates 31 and 32, held together by bars 33 and 34 70 threaded at their ends and provided with nuts which hold the frame together. At the center of the top member 31 is a screw 35 which extends down through a threaded hole in top plate 31, and is provided with a suitable 75 handle 36. In series between the clamp screw 35 and the condenser terminal 28 is inserted a leaf spring 37, as shown in Fig. 11. This spring consists of two leaves bolted together at their ends and drilled with the central 80 holes 38 and 39 to receive respectively the clamp screw 35 and condenser terminal 28. Thereupon, by handle 36 the condenser 25 is clamped against the bottom of its casing 26, which rests on the bottom plate 32 of the 85 press. This spring clamping is an important function which will be referred to. This clamp is shown in side elevation in Fig. 14. By means of the clamping in this press, the same highest practicable compression is obtained on the assembled condenser as was initially obtained by the clamping of the material-stack (Fig. 6) and as was maintained on the material-stack and on its sections after removal of the clamp from the material-stack. 90 In other words, by means of the clamp of Figs. 9 and 14 the sections of the assembly are now compressed together with the highest practicable mechanical compression. The condenser stack 25 in its casing 26 with clamp 100 applied as shown in Fig. 9, is now subjected to a process of pre-heating preliminary to the embedding operation. As shown in Figs. 9 and 10, the temporary head 29 is open at its top save for the cross member 30 (Fig. 10), 105 and has only side walls to constitute an upward extension of the side walls of casing 26.

The process of pre-heating consists in pouring hot wax through said head down into the space in casing 26 around the condenser 110 25, until both casing and head are filled; and thereafter, and while this paraffin is in the casing and head the heat of a Bunsen burner flame is applied to the bottom of the casing (similarly to Fig. 5) for the purpose of co-operating in heating thoroughly the casing and condenser 25, this latter being done by playing the gas flame around the exterior of the casing. This gas flame may be applied to the casing prior to the pouring in of the 115 paraffin, but if that be done care should be taken that such application be not excessive on account of the possibility of overheating and carbonizing the paraffin sheath or marginal paraffin around the condenser, and of 120 melting the soldered connections of the condenser sections, which should not be heated as high as 150° C.

The hot paraffin in the casing serves to thoroughly heat the condenser itself, thereby 125

liquefying the thin paraffin sheath surrounding the condenser and the portions of paraffin lying between the outer surfaces of the foil sheets in the spaces not filled by the mica sheets. At this stage, little or none of the original paraffin coatings remains on the portions of the sheets inside the stack. When the condenser is thoroughly heated and its said paraffin liquefied, the heating bath of paraffin 10 is poured out of the casing 26 and head 29, by an inversion of the entire apparatus of Fig. 9.

The condenser is now ready for its final paraffin-embedment in its casing, in an instance where the casing is to be provided with 15 a cover serving as part of a means to permanently compress the condenser within the casing.

In an instance, however, when the condenser is to be provided with a permanent 20 clamp small enough to enter the final condenser casing and function independent of the casing as in Figs. 12 and 13; and in particular when the provision of such a clamp independent of such casing permits the use of a 25 permanent clamp in resilient form, such resilient clamp is provided for the condenser before it has been subjected to the preheating just above described, that is, such permanent spring clamp is to be applied to the condenser 30 upon its first assembly, as shown in Fig. 8; (although preferably, in this case, the assembly is first compressed cold, its capacity measured while under such temporary compression which simulates its final compression, 35 and then the clamp removed, the capacity finally adjusted, and the permanent clamp applied). Such a permanent resilient or spring clamp is shown in one form in Fig. 12, where the condenser stack 25 has first been provided 40 with substantially heavy conducting leads 40 and 41 (Figs. 8, 12 and 15), from its top and bottom respectively, as shown, and clamped independently of the casing cover 60 (Fig. 15) and in electrical connection with high potential stud 28 and casing 26 respectively. Upon the assembled condenser 25 is applied a top insulating compression block 42, and a bottom compressing block 43 which may be of metal. The top insulating block 42 may be of layde or 50 any other suitable insulator which will withstand the treatment in hot paraffin and the high mechanical compression involved in my processes. The front of the condenser 25 shown in Fig. 12 is one of the sides of the assembly of Fig. 8 from which extend the foil bunches and at which the series connections are made and from which project the separating insulators 23 of Fig. 8. To the other two and flat sides of the condenser, i. e., the sides 55 formed of the edges of the mica sheets (Fig. 12), are placed spacing blocks 44 and 44^A of insulating material similar to that of top insulating block 42. These side insulating blocks 44 and 44^A serve to keep the stack in alignment and also to fill the space beneath

the top block 42 and to provide surfaces over which pass the wire 45, which constitutes the resilient clamp. This wire consists preferably of piano steel wire and is wound tightly around this assembly, as shown in Fig. 12, 70 while the assembly is maintained under the highest practicable mechanical compression as in any suitable temporary clamp or press, such as a C-clamp, a vise, or any other suitable form of press, such, for example, as that 75 shown in Fig. 6. While the assembly is under such compression, the wire 45 is wound with its turns tightly around the assembly and its ends fastened securely to maintain the high compression of the press before the 80 same is removed. The effect of the winding of this wire 45 is cumulative, each turn adding to the effect of the others in striving to increase the tension on the assembly. The insulating members 42, 44 and 44^A serve to insulate the 85 wire 45 from the stack and prevent electrical connection between the two ends of the stack which are of opposite potential. The compression on the stack is, of course, longitudinal between the top insulating plate 42 and the bottom compression plate 43. The above compression is effected while the condenser is cold. Thereupon the condenser, with its small clamp applied, may be removed from the large press and thoroughly heated in a 90 bath of paraffin at about 135° C. for about twenty minutes, the result being to thereby heat the condenser and liquefy the marginal paraffin on and about the condenser. This heating bath is preliminary to a further compression, but it also serves to drive out of and off from the condenser any air or moisture which may have been introduced into the marginal paraffin since the production of the condenser from the material-stack or since the 95 air and moisture were first previously washed out from the material-stack. If the cold compression just previous to this heating bath be omitted, i. e., if the condenser be subjected to the heating bath without being under substantial compression, then the value may be 100 lost of the advantages of the original hot compression of the material-stack, i. e., the substantial washing out of air and moisture from between the sheets in the interior of the stack. As the result of this heating bath, all the 105 paraffin yet remaining in and about the condenser (and at this stage there is very little, if any, paraffin left inside the condenser) is liquefied. The hot stack, yet and always hereafter under compression, is then removed from the heating bath and returned to the powerful C-clamp or arbor press, wherein the compression is again applied, but to a degree higher than when the condenser was cold. While under the high compression of the 110 press the permanent small clamp 45 is further tightened to maintain the compression attained by the large clamp or press, which at 115 this stage should have been set for about one 120

thousand pounds per square inch of active area of the overlapping portions of the foil sheets in the centre of the condenser. Such increase of compression and the further tightening of the permanent clamp are permitted when at this stage there is any paraffin remaining inside the stack as between the sections, such paraffin being of course soft as the result of the heating bath. Upon the tightening up (or rewinding) of the small permanent clamp, the condenser is removed from the large clamp or press. This operation, which is the final operation on the condenser stack itself, has resulted in yet more completely squeezing out any paraffin remaining between the sheets in the condenser and therefore in washing out any remaining air or moisture vapor within such paraffin. After the application of any such permanent spring clamp as in Fig. 12, the assembly of Fig. 12, which is the final complete condenser in an electrical sense, is placed in the casing 26 of Fig. 10, together with the temporary head 29 for the pre-heating preliminary to final embedding, which already has been described in connection with Figs. 9 and 10; but the clamping apparatus in Fig. 9 will not be needed now because the wire 45 of Fig. 12 already serves to provide the high resilient compression of the leaf spring clamp apparatus of Fig. 9. However, the top lead 40 (Fig. 15) may be connected to the condenser terminal 28 (Figs. 12 and 15), the latter being centered through the opening in the head 29 of Fig. 9, in order to center the condenser of Fig. 12 in the casing 26 of Fig. 9.

Whether there be used in the process first above described in connection with Figs. 9 and 10, the condenser of Fig. 9 with the temporary leaf spring 37, or the condenser of Fig. 12 with a permanent resilient clamp as 45, for example, the effect of the resilient compression during the heating bath in the casing 26 of Fig. 9 will be the same, i. e., when the condenser expands during the process of pre-heating in the paraffin bath in the casing 26 of Fig. 9, the resilient clamp will yield to prevent deformation of or injury to the stack, and at all times thereafter during the process (and thereafter in service in the case of the permanent clamp of Fig. 12) the spring clamp will yield during the heating or the cooling to conform to the length of the stack and at all times uniformly exert the desired uniform high compression.

Thereupon, in the case of the condenser of Fig. 9 or the condenser of Fig. 12, after the pre-heating bath of paraffin of Figs. 9 and 10 is poured off from the casing 26, the assembly of the casing, condenser and spring clamp (i. e., either the temporary leaf spring clamp of Fig. 9 or the permanent spring clamp of Fig. 12) is inserted in the apparatus of Fig. 13 for the purpose of being subjected to the production of the permanent embedment of

the condenser in hot paraffin preliminary to the final stage of cooling. For this purpose one or more of such assemblages (two as shown in Fig. 13) are placed in tank 46, which is used primarily as a vacuum tank, tube 47 at the left being in communication with a vacuum pump and provided with a valve 48. The insertion of the condensers in this tank should be made immediately upon pouring off the preceding paraffin heating bath and while the stack is yet as hot as possible, and the subjection to the vacuum treatment should also be effected immediately. This vacuum should be a fairly high vacuum of the order of a few millimeters, at preferably not much higher pressure than 3 millimeters. The vacuum treatment need not be applied to the stack for more than a few minutes, because it does no good save while the stack is hot and its marginal wax is liquefied or soft, the object of the vacuum treatment being to remove air and moisture from the liquid or soft marginal wax in preparation for the process next to be effected, of enveloping the stack in hot paraffin for eventual cooling and embedment.

All this time the stack is under the above-described mechanical compression of either the leaf spring 37 of Fig. 9 or the permanent spring clamp 45 of Fig. 12.

While the vacuum is yet applied to the condensers in the tank 46, hot paraffin for the permanent embedding is flowed in around the condenser in each casing until not only is the stack completely submerged in the paraffin, but the head 29 also (Fig. 9) on top of the casing above the stack is completely filled with the hot paraffin, so that a fluid head of melted paraffin is established above that part of the filler which lies in the vicinity of the insulating portion of the casing and of the neighboring metal parts of the casing and high potential terminal. The maintenance of the vacuum around the stack until the latter is submerged in the paraffin serves to prevent the entrapping of any air or gaseous vapor in any portions of the final embedding paraffin, which may be so close to the condenser as to permit electrical losses or breakdowns in service due to such air or moisture. While the hot embedding paraffin is being flowed into the exhausted space around the condenser, the air or vapor which may have been in the marginal paraffin of the condenser and which has been removed therefrom by the vacuum and attenuated and distributed through the vacuous space in the tank is prevented by the continuation of the vacuum from being concentrated or entering again into the marginal wax. Thus, the inflowing paraffin from pipes 49, branching from pipe 50, connected to paraffin reservoir 51, can, upon entering the condenser casings, merge with the hot marginal condenser paraffin freed of air and moisture, the incoming paraffin having been also freed of air and mois-

ture by heating. In some instances, a satisfactory condenser may be produced without the application of the paraffin in the above precise fashion, but when the best possible 5 condenser is desired these processes of vacuum and filling in embedding paraffin while under vacuum are extremely important.

An equalizer pipe 63 is connected between the wax reservoir 51 and the tank 46. Its 10 function is to make the gas pressure on wax in reservoir 51 at all times equal to that in tank 46, the reservoir 51 being provided with an air-tight cover 65. Then, regardless of any application of vacuum (or air pressure) 15 to tank 46, the paraffin will flow from reservoir 51 into the condenser casings in vacuum tank 46 under gravitational head only; that is, the head given by the elevation of the reservoir 51 above tank 46. Thus, the paraffin 20 may flow by gravity from reservoir 51 to the condenser casings in tank 46, irrespective of the air pressure in the latter. In equalizer pipe 63 there is placed a two-way valve 64 for the purpose of throwing the pipe 25 63 out of service whenever desired, valve 64 being then turned to open the reservoir 51 to the atmosphere. The other or normal position of valve 64 simply places in communication with one another the air-spaces in 30 reservoir 51 and tank 46.

At any time after the inflowing paraffin has submerged the condenser in its casing, the vacuum treatment can be terminated by the closing of valve 48 in the tube to the 35 vacuum pump, and by the opening of the bleeder valve 52 in the pipe at the right communicating with the outside air. However, during the paraffin filling, the remenant air or vapor which has come from the stack or 40 incidentally from the inflowing paraffin, highly expanded in the vacuous space in tank 46 on account of the greatly reduced pressure on the paraffin due to the vacuum, will have risen up through the hot paraffin in 45 the condenser casing to points at or near its surface, where it may exist in the form of foam or froth just below the surface. Thereupon these bubbles just beneath the surface will break through the surface and disappear 50 in the space in the tank. Therefore, it is preferable not to shut off the main paraffin valve 53 until after this froth has disappeared and, therefore, until after both the casing and the head 29 are completely filled with paraffin 55 substantially freed of air. Preferably also the valve 52 is not opened to let the outside air into tank 46 until after said filling has been completed.

After main paraffin valve 53 has been 60 closed, and before bleeder valve 52 is opened, and before paraffin has solidified in pipes 49, valve 54 is opened in pipe 50 (the end of which is open to the atmosphere), in order to cause atmospheric pressure to force paraffin 65 remaining in pipes 49 against the reduced

pressure in tank 46, for the purpose of clearing the pipes and preventing their being stopped up by cooled and solidified paraffin. The additional amount of paraffin thus flowed into the condenser casings is small, as the 70 pipes 49 are small.

As an example of the general size and proportion of the head 29, it may be stated that for a condenser casing 26 (Fig. 9) about 3 1/2" high and 4 1/2" long by 3" wide (internal dimensions), the head 29 may be of the same length and width but about 3/4" in height; but the head 29 may be of much greater height, i. e. as high as or higher than the casing 26 itself, if desired, without deleteriously 80 affecting the operation of my processes.

The next process is that of cooling the paraffin which has been flowed into the casing around the condenser as in Fig. 13. This is illustrated in connection with Fig. 14 as 85 a special manner of executing the process.

This manner is important in any case where it is desired to have the embedding paraffin holosteric, i. e. freed of all voids. This process consists in certain treatment which is 90 applied during the solidification of the paraffin inside the casing 26 and head 29. This treatment consists, generally speaking, in solidifying the embedding paraffin from its bottom upwards, i. e. in cooling the bottom 95 more rapidly than the top and all in a progressive manner. This may be effected either by (1) abstracting heat from the bottom without doing anything to the top paraffin, or (2) by applying heat to the top paraffin while permitting the bottom to gradually cool upwards as by room temperature, or (3) by abstracting heat from the bottom while applying heat to the top. Specifically, the latter is preferable for economy of time and 100 in giving better control of the gradual execution of the process. In practice, the last or preferable manner has been effected by inserting the condenser casing 26 in a shallow pan or tray 55 containing water, which may 105 be renewed from time to time, or consists of water circulation. Alternatively and preferably, an air blast from blower 56 may be directed against the lower portions of the sides and the bottom of casing 26 in the 110 absence of water tray 55. The air blast may be directed against the desired lower portions of casing 26 by means of flexible tubing 57. And, as part of said preferred manner of executing the process of gradual cooling from 115 the bottom upwards, the upper part of the liquid paraffin body in casing 26 and head 29 may be and has been successfully in practice, heated as by pouring in additional hot paraffin from time to time, which, indeed, is useful 120 also to compensate for the shrinkage of the paraffin in the casing as its contracts due to its temperature being lowered and to its solidification. The heating is effected additionally, when desired, by means of a remov-

125
130

able electrical heating coil 58 mounted circumferentially around head 29; or alternatively with such coil the flame of a Bunsen burner may be played around the walls of head 29 and around the upper part of casing 26.

In Fig. 14 is represented in dotted lines the condenser 25 with all of the temporary clamping apparatus of Fig. 9, including the leaf 10 spring 37; but when the permanent spring clamp of Fig. 12 is used, such temporary spring clamp apparatus will not be used, and the apparatus subjected to the cooling treatment of Fig. 14 will consist simply of the condenser casing 26 containing condenser 25 in its spring clamp 45 of Fig. 12, and the temporary head 29, heating coil 58, and any of the described means for abstracting heat from the lower portion of the liquid paraffin in the 20 condenser casing, and adding heat to the top.

The importance of this cooling treatment gradually from the bottom upwards, particularly in connection with the head 29 on top of casing 26, or of the equivalent of this 25 process, is due to the fact that the cooling of paraffin or any substantial equivalent waxes which can be used for these condensers is accompanied by a large decrease in volume, such that without this process an ordinary 30 or uniform cooling from all sides would result first in the cooling of an exterior shell and the cooling and contraction of the interior, which would result in the formation of interior voids or cracks, which, in turn, might 35 be filled with gases or vapors which had been entrained in the paraffin or with atmosphere drawn in from outside the paraffin; and such ordinary process of solidification or freezing would result, as ordinarily, in the driving 40 away from the surfaces of solidification toward the central liquefied portions of all foreign materials, this central portion in the casing of a condenser being the stack itself, from which it is extremely desirable that all 45 such foreign materials be removed as far as possible. With my process of cooling gradually from the bottom upwardly, the above action is avoided and on the contrary the surfaces of solidification, gradually moving 50 upwardly, drive before them all such foreign materials and, not only that, but force them up beyond the vicinity of the upper or high potential end of the condenser and out of the casing 26 entirely further up into the paraffin 55 contained in the head 29. Hence, the permanent embedding paraffin in the casing (as distinguished from the temporary paraffin in the temporary head 29) is made substantially solid, and voids otherwise tending to become 60 fixed in the upper part of casing 26, in the neighborhood of the upper or high potential end of the condenser, are caused to be established, if anywhere, in the temporary paraffin in the temporary head 29. Also, the use of 65 head 29 in connection with the repeated addi-

tion of hot paraffin to compensate for the shrinkage during cooling, prevents the formation of a final depression in the paraffin in the top of casing 26, so that the final cooling of the top of the paraffin in the casing results 70 in a uniform mass of paraffin free from any lines of cleavage which might exist in the paraffin in the casing if it were allowed to solidify with a depression in its top surface and if after solidification additional paraffin 75 were added to fill up the depression.

Upon the application of this solidification process, the paraffin commences to solidify at the bottom of the casing and at lower portions along the sides of the casing and the 80 sides of the stack resting on the bottom of the casing 26, the rest of the paraffin in the casing 26 and head 29 remaining liquid. As this cooling process is continued (which may be several hours, depending upon the size of 85 the condenser and depending upon the particular means for cooling and heating employed, the air blast above described being more efficient than the water cooling), the solidification extends higher up from the bottom of the casing and still higher up inside 90 the sides thereof and along the sides of the condenser, so that the remaining liquid paraffin is U-shaped in cross-section around the condenser. Thus, as the solidification gradually extends upwardly, the liquefied remainder at all times bears down upon and against the upwardly moving surfaces of 95 solidification and directly follows up the shrinkage or contraction at such surfaces accompanying the solidification, to the end of preventing voids or cracks. Meanwhile, as stated above, the surfaces of solidification drive upwardly any remnant air or moisture, not only to the upper part of the casing 26, 100 but up into the head 29. If the head 29 be sufficiently high to contain a sufficient volume of paraffin, then all the air and moisture as well as voids finally forming near the upper 105 surface of the paraffin will be contained wholly within the head, so that when later the temporary wax in the head 29 is cut off, there will be left no voids, air holes or depressions in the upper part of the casing in 110 the vicinity of the condenser. In instances 115 when the execution of this cooling process involves specifically the application of heat (as in the preferred form) to the paraffin in the head 29, such application of heat may be discontinued after assurance is obtained by observation that solidification has been completed of all the paraffin within the casing 26. It is to be understood that this cooling operation is conducted under at least atmospheric 120 pressure, so that the atmosphere has access to the top of the molten paraffin in head 29, in order to assist in the cooling process in respect of the prevention of voids in the paraffin in casing 26. If desired, this air or gas 125 pressure on top of the molten paraffin body 130

may be greatly increased above atmospheric pressure, this increased pressure being advantageously as high as 150 pounds, which can be maintained until complete solidification 5 has been effected. The effect of such increased pressure is to compress any voids or bubbles in the paraffin, thereby making their effect less deleterious. For this purpose, the condenser in its filled casing may be left in 10 tank 46 of Fig. 13 for the execution of the cooling process, and compressed air from a suitable pump may be introduced into the tank 46 by way of valve 52. Also, the application of additional wax into the head 29 during 15 the cooling process may be effected by way of the pipes 49 from the paraffin reservoir 51, in which case, of course, the paraffin in reservoir 51 should be subjected to at least the same gas pressure as that of the tank 46 by way of valve 64, in order to permit the inflow of paraffin into tank 46.

Throughout the above paraffin embedding process and ever since the condenser stack has been assembled, it has been under the highest 20 practicable mechanical compression either by way of a temporary rigid clamp, a temporary spring clamp or a permanent spring clamp adapted to be received with the stack into the final condenser casing. If the clamp be a 25 temporary clamp as illustrated in Figs. 9 and 14, it is removed upon the complete solidification of the embedding paraffin; but when such temporary clamp is employed and duly removed, it should be replaced with the clamp 30 which is to be permanently assembled with the condenser in service, as soon as possible after the removal of the temporary clamp; for even although the embedding paraffin be 35 completely solidified before the removal of the temporary clamp, such solid paraffin is liable to cold flow and, therefore, is liable 40 to permit expansion of the stack under heating conditions which may be encountered in service, and this should never be permitted. 45 For this reason, it is preferable, as stated above, to employ some such form of permanent clamp as that illustrated in Fig. 12, or another form of spring clamp such as that 50 shown in my application, Serial No. 292,126, filed April 23, 1919; of which the present application is a continuation in part, and such permanent clamp should be applied to the condenser at the earliest possible stage in the process, even at the stage when the stack has 55 been treated to the paraffin bath as in Fig. 5, just before it is subjected to the washing out process illustrated in Fig. 6.

With further reference to Fig. 14. After the solidification of paraffin is completed, the head 29 is removed from the casing and from the paraffin in the head above the casing, this removal being readily permitted upon the application of heat from removable heater 58 or of a gas flame to the outside of the walls 60 of head 29. Then, by means of a long knife

the paraffin which projects up out of casing 26, being that which was formerly inside the head 29, is cut and chipped off and then pared or shaped to a level with the top of the casing. In cases where a temporary clamp has been 70 used thus far to maintain the high compression during the processes, there can now be applied to the condenser any suitable means of permanently clamping it in its casing; for example, a construction may be provided 75 whereby the application of a cover to the top of the casing will serve in any well-known manner to compress the condenser in the casing. Preferably, however, as when a permanent small clamp (as in Fig. 12) is employed 80 in the processes, such permanent clamp (as 59, Fig. 15) is left on the condenser in the casing and any suitable cover 60 is applied to the top of the casing over the embedding paraffin. The modified form of 85 small permanent clamp in the casing, which is shown in Fig. 15, comprises a U-shaped steel yoke 59 which embraces the condenser. The U-end is insulated from the condenser as by a stack of mica sheets 62. Two of these 90 clamps are disposed symmetrically on the condenser. The two ends of each clamp are entered by adjusting screws 61 which pass up through a steel spring plate 43^A (common to both clamps), whereby plate 43^A is flexed 95 to apply the desired compression. Mica stack 62 is placed on top of insulating plate 66 (as of bakelite) which in turn rests on metal plate 27 which transmits the pressure of the clamps 59 to the condenser. Insulating 100 plate 66 insulates the lead 40 from the top of the condenser. The condenser terminal 28 is soldered at its bottom to the upper end of strip lead 40.

The condenser terminals may be brought 105 out through the casing in any desirable or well-known manner as (Fig. 15) the high potential terminal 28 through an opening in insulating cover 60; and one terminal (that of low potential) may be constituted by the 110 metal casing 26 itself, pursuant to the common practice.

The above advantages of the embedding and cooling operations may be obtained, if desired, by providing a threaded opening 70 115 and a plug 71 therefor in the bottom of the casing for the inflowing of embedding paraffin, the casing (with its final cover applied and connection or connections made therethrough) being inverted during the filling 120 and cooling operations, and after solidification, the bottom opening closed up. By such an operation, one may avoid the use of the temporary head 29 (Fig. 9), for the condenser would be centered in its casing by assembly with the cover of the casing (Fig. 15), the assembled condenser and cover being applied in and to the casing; and the filling of the space in the inverted casing produces an even higher fluid head on the filler in the vi- 130

cinity of the high potential insulating portion of the casing than is obtained by temporary head 29 of Fig. 29. Thus, with the casing with cover applied (Fig. 15), but inverted during filling and solidification, and the high potential terminal-end of the condenser (top Fig. 15) lying in what is temporarily the bottom of the container of liquid paraffin (Fig. 14), and the supply of heat to the upper portion of the filler, the paraffin begins to cool at the bottom around the high potential end of the condenser, and the paraffin thereabove bears down on the upwardly extending surfaces of solidification, thereby preventing the formation of voids or cracks near the high potential end; and any cracks or voids in the paraffin near the low potential end of the condenser would be relatively innocuous. Also the paraffin by this method is caused to adhere to the inside surface of the cover of a casing, as the result of being applied thereto when hot and molten. This condition of the insulating wax at the neighboring condenser portions of high potential difference assists in preventing electrical brushing, reduces the tendency to creepage and prevents absorption of moisture at locations where moisture would produce serious results.

When a permanent condenser clamp is used or the stack is properly and permanently clamped inside the casing by any means, it is not so important that the foil sheets be non-resilient, for such clamp at a sufficiently early stage in the process will serve to maintain the desired intimacy of contact between mica and foil sheets, which excludes everything foreign from between the sheets. And even when a permanent condenser clamp be not used, the foil sheets may have some degree of resiliency without resulting in breaking down the hermetical sealing by the marginal sheath of paraffin, especially if the stack in the early stages of the process have a sufficient thickness of marginal sheath to prevent expansion of the stack (laterally with respect to the stack), and this may be obtained if necessary by suitable dipping in the paraffin bath for the purpose of obtaining such substantial thickness of the marginal paraffin.

Whenever compression or clamps are referred to herein, such compression is to be understood to be the highest mechanical compression which is practicable to be applied on the soft lead-foil sheets, and this in practice is about 1,000 pounds or more per square inch of the active area of each mica sheet, i. e., that part of the mica sheet which lies between the overlapping foil sheets, this being a pressure which amounts to about a ton or more on the entire end surface of an ordinary condenser 3" high by 2" long by 1½" wide.

When the word "paraffin" is used in the claims, it is intended as applying to any ma-

terial which is the substantial equivalent of the paraffin-carnauba mixture preferred herein. As to the limitation to sheets of mica, it is to be understood that this does not exclude other materials which might be found to be equivalent within the invention, as to the valuable properties of mica for this purpose involving its low dielectric losses, its non-porous character, its ability to be formed into thin sheets of sufficient mechanical strength for my processes, and its high dielectric constant which permits production of a high capacity condenser of small volume.

I claim:

1. The method of making an electrical condenser stack of non-porous dielectric sheets and metal sheets which consists in first coating the active non-porous surfaces of the sheets, prior to stacking them together, with a dielectric detergent liquid; thereafter stacking the sheets; and thereafter employing the detergent layers between the sheets in the stack to wash out air or moisture from between the sheets, by squeezing the sheets together when the detergent layers are liquid, thereby forcing out said layers with any entrained air or moisture from between adjacent sheets and permitting the non-porous surfaces of adjacent pairs of sheets, so freed of air and moisture between them, to lie together in intimate surface contact with one another in the stack.

2. The method of making an electrical condenser stack of non-porous dielectric sheets and metal sheets which consists in causing the sheets to adhere together during the stacking operation by first coating their active non-porous surfaces, prior to stacking, with a normally solid dielectric detergent in hot molten condition; thereafter stacking the sheets together when the coating on at least one of the facing surfaces of two adjacent sheets is warm enough to cause adherence of such surfaces; and subsequent to stacking, employing the detergent layers between the sheets in the stack to wash out air or moisture from between the sheets, by squeezing the sheets together when the detergent layers are liquid, thereby forcing out said layers with any entrained air or moisture from between adjacent sheets and permitting the non-porous surfaces of adjacent pairs of sheets, so freed of air and moisture between them, to lie together in intimate surface contact with one another in the stack.

3. The method of making an electrical condenser stack of non-porous dielectric sheets and metal sheets which consists in causing the non-porous surfaces of adjacent stack sheets to adhere together temporarily during the stacking operation, by first coating the active non-porous surfaces of individual sheets, prior to stacking them together, with a normally solid dielectric detergent in hot

molten condition, and then stacking such sheets together before said coatings on the facing surfaces of pairs of adjacent sheets being stacked together have cooled and solidified; and, subsequent to such stacking, employing the detergent layers to wash out air or moisture from between the stack-sheets, by squeezing the stack-sheets together when the detergent layers are in heated liquid condition thereby forcing out said layers with any entrained air or moisture from between adjacent sheets and causing the non-porous surfaces of adjacent sheets, so freed of air and moisture between them, to be squeezed together in intimate surface contact with one another in the stack.

4. The method of making an electrical condenser stack of non-porous dielectric sheets and metal sheets which consists in first 20 coating the active non-porous surfaces of the sheets, prior to stacking them together, with a normally solid dielectric detergent in hot molten condition; thereafter stacking the sheets together; and, subsequent to such 25 stacking; employing the detergent layers between the sheets in the stack to wash out air or moisture from between the stack-sheets, by squeezing the stack-sheets together when the detergent layers are in heated liquid condition, thereby forcing out such layers with any entrained air or moisture, from between adjacent sheets, and causing the non-porous surfaces of adjacent pairs of sheets, so freed of air and moisture between them, to be 30 squeezed together in intimate surface contact with one another in the stack.

5. The method of making an electrical condenser stack of non-porous dielectric sheets and metal sheets which consists in first coating 40 the active non-porous surfaces of the sheets, prior to stacking them together, with a normally solid dielectric detergent in hot molten condition; thereafter stacking the sheets together; causing the coated sheets to 45 adhere to one another during the stacking operation and preventing unnecessary thickness of detergent layers in the stack, by applying heat to the stack during its building thereby maintaining in liquid condition the 50 detergent layers in the growing stack, causing excess detergent material to be squeezed out from between lower earlier stacked sheets of the growing stack by the gravity of upper later stacked sheets; and, subsequent to such 55 stacking, employing the detergent layers between the sheets to wash out air or moisture from between the stack-sheets, by squeezing the stack-sheets together when the detergent layers are in heated liquid condition, thereby 60 forcing out such layers with any entrained air or moisture, from between adjacent sheets and causing the non-porous surfaces of adjacent pairs of sheets, so freed of air and moisture between them, to be squeezed together

in intimate surface contact with one another 65 in the stack.

6. The method of making an electrical condenser stack of non-porous dielectric sheets and metal sheets which consists in first coating the active non-porous surfaces of the 70 sheets, prior to stacking them together, with a normally solid dielectric detergent in hot molten condition; thereafter stacking the sheets; removing some of the air or moisture entrapped in the layers of detergent between 75 the sheets by subjecting the stack to a sufficiently prolonged bath in hot molten dielectric material; and thereafter squeezing the stack sheets together when the detergent layers are in liquid condition until such layers with any 80 remaining entrained air or moisture have been forced out of the stack and formed into a thin sheath of cooled and solidified dielectric material around the edges of the sheets and the sides of the stack, said solidified 85 sheath holding the sheets together in the stack in intimate surface contact with one another after the removal of the detergent layers from between them and after the discontinuance of the squeezing out pressure. 90

7. The method of making an electrical condenser stack of non-porous dielectric sheets and metal sheets which consists in first coating the active non-porous surfaces of the sheets, prior to stacking them together, with 95 a normally solid dielectric detergent in hot molten condition, thereafter stacking the sheets; thereafter washing out air or moisture from between the non-porous stacks of the resulting stack by squeezing the stack 100 sheets together when the detergent layers are in liquid condition, thereby forcing out the detergent, with any entrained air or moisture, from between adjacent sheets and causing the non-porous surfaces of adjacent 105 sheets, so freed of air and moisture between them, to be squeezed into intimate surface contact with one another in the stack; said squeezed out detergent dielectric forming in a thin dielectric sheath around the edges of 110 the sheets and the sides of the stack; and continuing said squeezing operation until said dielectric sheath is solidified by cooling sufficiently to hold the sheets in their intimate surface contacts independently of such squeezing. 115

8. The method of making an electrical condenser comprising a stack of non-porous dielectric sheets and metal sheets enclosed in a casing which consists in first coating the active non-porous surfaces of sheets, prior to 120 stacking them together, with a normally solid dielectric detergent in hot molten condition; thereafter stacking the sheets, thereafter washing out air or moisture from between the non-porous stack sheets by squeezing them 125 together when the detergent layers between them are in liquid condition thereby forcing out said detergent, with any entrained air or

moisture, from between adjacent sheets and causing the non-porous surfaces thereof, so freed of air and moisture between them to be squeezed into intimate surface contact with 5 one another in the stack; said squeezed-out detergent forming in a thin dielectric sheath around the edges of the sheets and the sides of the stack; continuing said squeezing until said dielectric sheath has solidified by cool- 10 ing sufficiently to hold the sheets in their intimate surface contact independently of the squeezing; discontinuing the squeezing; placing the dielectric-sheathed stack in an enclosing casing, spaced from the walls thereof and 15 under high mechanical compression in the casing; softening said dielectric sheath in the casing by heating; subjecting the entire as- 20 sembly while said sheath is soft, to vacuum; and, while continuing the application of the 25 vacuum and the high mechanical compression, pouring hot molten normally solid dielectric as a filler into said space, thereby re- 30 moving air or moisture from the sheath and maintaining the intimacy of surface contact 35 of the sheets when the molten filler melts the sheath and until the entire dielectric filler has 40 solidified as an embedment of the stack.

9. The method of making an electrical condenser comprising a stack of non-porous dielectric sheets and metal sheets enclosed in a 45 casing which consists in first coating the active non-porous surfaces of the sheets, prior to stacking them together, with a normally solid dielectric detergent in hot molten condition; thereafter stacking the sheets; there- 50 after washing out air or moisture from be- 55 tween the non-porous sheets of the stack by squeezing the stack sheets together when the detergent layers between them are in liquid condition, thereby forcing out said layers and any entrained air or moisture from between adjacent sheets; continuing such squeezing until the squeezed-out detergent dielectric has 60 cooled and solidified in a sheath around the 65 edges of the sheets and sides of the stack hav- 70 ing the ability to hold the sheets in their inti- 75 mate surface contact caused by the squeezing out of the detergent, air and moisture; discontinuing the squeezing operation when said 80 dielectric sheath has cooled and solidified to 85 hold the sheets in their intimate surface con- 90 tact; placing the stack in a casing proportioned relative to the stack to provide a space 95 between stack and casing; pouring hot molten 100 normally solid dielectric into such space thereby melting the dielectric sheath around the stack, while maintaining the stack under high mechanical compression in the casing holding the sheets in intimate 105 surface contact after melting of the dielectric 110 sheath and during the solidification of the dielectric in said space.

10. An electrical condenser comprising a 115 stack of sheets of non-porous dielectric and metal sheets and a casing enclosing such 120 sheets and proportioned thereto to provide a space between the sides of the stack and the casing, said space being filled partially with a sheath of normally solid dielectric material around the stack, leaving their surfaces in intimate contact with one another; and said 125 space being further filled with a comparatively thick mass of normally solid dielectric material; said two masses of dielectric material being solidified together and constituting a permanent embedment of the stack in the casing; and means holding the stack under high mechanical compression in the casing, thereby maintaining the intimate surface contact of the stack-sheets during the solidification of the entire mass of dielectric in the space between the stack and casing.

11. The method of making an electrical condenser stack of non-porous dielectric sheets and metal sheets which consists in caus- 85 ing the non-porous surfaces of adjacent stack sheets to adhere together during the stacking operation, by first coating them, prior to stacking, with a dielectric detergent in hot molten condition; thereafter stacking the sheets when the coatings are in adherent con- 90 dition; subjecting the resulting stack to a bath in hot molten dielectric; washing out air or moisture from between the non-porous stack sheets by squeezing them together when the detergent dielectric layers between 95 the sheets are in liquid condition, the squeezed-out dielectric being thereby formed into a sheath around the edges of the sheets and the sides of the stack, which is able to hold the sheets in intimate surface contact 100 after discontinuance of the squeezing opera- 105 tion; discontinuing the squeezing operation; placing the sheathed stack in a casing proportioned to provide a space between the stack and the casing; and pouring hot molten dielectric material into said space, thereby melting said dielectric sheath, while maintaining the stack under high mechanical compression in the casing holding the sheets in intimate 110 surface contact after melting of the dielectric sheath and during the solidification of the dielectric in said space.

12. The method of making an electrical condenser stack of non-porous dielectric sheets and narrower and longer metal sheets, which 115 consists in first coating the active non-porous surfaces of the sheets, prior to stacking them together, with a dielectric detergent liquid; thereafter stacking the sheets, placing the metal sheets in positions wherein those of 120 opposite polarity project out from different portions of the stack and elsewhere are spaced inwardly of the edges of the dielectric sheets; mechanically holding the edges of the stacked dielectric sheets to maintain them in common 125 alignment in the stack while squeezing all the sheets together, thereby squeezing out the detergent layers and any entrained air or mois-

ture without disturbing the stacked relation of the sheets to one another by the squeezing operation.

13. The method of making an electrical condenser stack of non-porous dielectric sheets and narrower and longer metal sheets, which consists in first coating the non-porous surfaces of the sheets, prior to stacking them together, with a dielectric detergent liquid; thereafter stacking the sheets, placing the metal sheets in positions wherein those of opposite polarity project from different portions of the stack and elsewhere are spaced inwardly of the edges of the dielectric sheets; mechanically holding the edges of the stacked dielectric sheets to maintain them in common alinement in the stack while removing some of the moisture from the detergent layers by submerging the stack in hot molten dielectric material.

14. The method of making an electrical condenser comprising a stack of non-porous dielectric sheets and metal sheets enclosed in a casing proportioned to provide a space between stack and casing, which consists in first coating the active non-porous surfaces of the sheets, prior to stacking them together, with a dielectric detergent liquid; thereafter stacking the sheets, forming layers of detergent between the sheets; thereafter squeezing out the detergent layers, when in liquid condition, together with any entrained air or moisture, from between the sheets, permitting the sheets to lie together in intimate contact with one another within the stack; thereafter placing such stack in the casing with its high potential portion near an opening in the casing, the stack being held under high mechanical compression in the casing; and then pouring a hot molten mass of normally solid dielectric material into said space and maintaining a fluid head of said material acting in the vicinity of high potential portion of the stack and the casing opening, to cause holosteric solidification of the molten filler in said vicinity.

15. In the art of making mica condensers, the process consisting in building a condenser stack of sheets which first have been coated with paraffin before stacking; removing some of the moisture from between the sheets and the stack by liquefying the paraffin coatings by immersing the stack in hot molten paraffin; squeezing the liquid paraffin and any contained air or moisture from between the sheets of the stack by the application of high mechanical pressure across the stack ends; and cooling the stack while maintaining such squeezing-out pressure, thereby solidifying the paraffin adhering to the sides of the stack on the edges of the sheets.

16. The method of producing mica and foil sheet condensers having clean active surfaces of the sheets, and keeping the same clean, which consists in building a stack of such

sheets each first coated with molten paraffin before stacking, and keeping the growing stack warm and the coatings thereby soft during the stacking operation; subjecting such stack, with liquid paraffin layers between the sheets, to high mechanical compression, thereby squeezing out said layers with any entrained air or moisture and causing the sheets to lie in intimate surface contact with one another; placing such stack into a permanent casing and under high mechanical compression therein, with the edges of the stack sheets spaced from the casing; and filling such space with hot molten paraffin.

17. The process of building mica and foil sheet condensers which consists in piling such sheets on top of one another face to face in a stack, dipping each sheet in molten paraffin before placing it in the stack; utilizing the weight of the upper part of the growing stack to squeeze out some of the paraffin from between the sheets of its lower part, by keeping the sheet coatings molten during building by the application of heat to the stack additional to the heat of the warm coatings of freshly stacked sheets; and finally solidifying the paraffin between and at the edges of the sheets thereby causing the sheets to adhere to one another and permit convenient handling of the stack in further treatment without impairing its unitary character.

18. The process of building a series-sectional high potential mica and foil sheet condenser which consists in piling such sheets on top of one another face to face in a stack, first dipping each sheet in molten paraffin before placing it in the stack; placing section separators on top of each section of desired electrical capacity; utilizing the weight of the upper part of the growing stack to squeeze out some of the paraffin from between the sheets of its lower part by keeping the sheet coatings molten during building, by the application of heat to the stack additional to the heat of the warm coatings of freshly stacked sheets; and finally solidifying the paraffin between and at the edges of the sheets, thereby causing the sheets to adhere to one another and to permit convenient handling of the stack in further treatment without impairing its unitary character.

19. The method of making an electrical condenser stack of non-porous dielectric sheets and metal sheets which consists in first coating the active non-porous surfaces of the sheets, prior to stacking them together, with a normally solid dielectric detergent in hot molten condition; thereafter stacking the sheets; thereafter, when the layers of detergent between the stack sheets are cool and solid, applying heat to the stack to melt said layers; and, while said layers are molten, employing them to wash out air or moisture from the interior of the stack, by squeezing them out as vehicles for conveyance of entrained air or

moisture, thereby permitting intimate surface contact of the sheets without intervening air or moisture.

20. The method of making an electrical condenser stack of non-porous dielectric sheets and metal sheets, which consists in first coating the active non-porous surfaces of the sheets, before stacking them together, with a normally solid dielectric detergent in hot molten condition; thereafter stacking the sheets; thereafter removing some of the air or moisture entrained in the layers of detergent between the sheets by subjecting the stack, not yet subjected to compression squeezing out the detergent layers from between the sheets, to a bath in hot molten dielectric material which melts the detergent layers, vaporizes some of the moisture entrained therein and receives such vapor; and thereafter cleaning the active surfaces of the sheets from remaining air or moisture entrained in the detergent layers by squeezing the latter from between the sheets and out of the stack.

21. The method of making an electrical condenser stack of non-porous dielectric sheets and narrower and longer metal sheets, which consists in first coating the non-porous surfaces of the sheets, before stacking them together, with a dielectric detergent liquid; thereafter stacking the sheets, placing the metal sheets in positions wherein those of opposite polarity project out from different portions of the stack and elsewhere are spaced inwardly of the edges of the dielectric sheets; mechanically holding the edges of the stacked dielectric sheets to maintain them in common alinement in the stack; immersing the stack not yet subjected to compression squeezing out the layers of detergent from between the sheets, in a bath of hot molten dielectric which melts the detergent layers, vaporizes some of the moisture entrained in such layers and receives such vapor, the dielectric sheets being mechanically held in alinement during said bath; and thereafter while said dielectric sheets are continued to be mechanically held in alinement, cleansing the active surfaces of the sheets from remaining air or moisture entrained in the detergent layers by squeezing the latter in liquid condition from between the sheets and out of the stack.

22. The method of making an electrical condenser stack of non-porous dielectric sheets and narrower and longer metal sheets, which consists in first coating the non-porous surfaces of the sheets, before stacking them together, with a dielectric detergent liquid; thereafter stacking the sheets, placing the metal sheets in positions wherein those of opposite polarity project out from different portions of the stack and elsewhere are spaced inwardly of the edges of the dielectric sheets; and immersing the stack not subjected to compression squeezing out the layers of detergent from between the sheets, in

a bath of hot molten dielectric which melts the detergent layers, vaporizes some of the moisture entrained in such layers and receives such vapor, the dielectric sheets being mechanically held in alinement during said bath.

23. The method of making an electrical condenser stack of non-porous dielectric sheets and metal sheets, which consists in causing the sheets to adhere together during preliminary operations by first coating them, before stacking them together, with a liquid dielectric detergent which entraps the air and moisture on the surfaces of the sheets; thereafter stacking the sheets when their coatings are adherent thereby retaining them in the positions in which they are stacked; thereafter washing air or moisture out of the stack by squeezing the sheets together forcing out the layers of liquid detergent from between the sheets together with any entrained air or moisture; and preventing lateral slipping of the sheets from their stacked positions during such squeezing and while the liquid detergent remains between them, by mechanically holding the edges of the sheets in alinement.

24. The method of making an electrical condenser of a stack of metal armature sheets and non-porous dielectric sheets, which consists in first removing air and moisture from the surfaces of the sheets in the stack by squeezing out a normally solid dielectric detergent in molten condition and solidifying the squeezed-out detergent at the margins of the stack sheets while yet the squeezing-out compression is applied; subsequently transferring such stack to a metal casing connecting a terminal of the stack to the casing as a condenser terminal; and subsequently, while the stack is under high mechanical compression in the casing and while the marginal detergent is soft, applying a vacuum around the stack, thereby removing air from the soft marginal detergent; and subsequently, while the stack remains under high mechanical compression; and insulating the higher potential portions of the stack from the metal casing terminal by inserting an insulating material similar to said dielectric detergent, and in molten condition, in the casing and in a thick mass around the stack and its high potential lead and between the stack and high potential lead on one hand and the metal casing on the other; and maintaining a fluid head of said molten insulating material around the stack lead and the highest potential portions of the stack, until said insulating mass has solidified; said insulating mass melting the marginal detergent and being merged with it.

25. The method of making an electrical condenser of a stack of metal armature sheets and non-porous dielectric sheets, which consists in first removing air and moisture from

- the surfaces of the sheets in the stack by 5
squeezing out a normally solid dielectric detergent in a molten condition and solidifying the squeezed-out detergent at the margins of
5 the sheets on the sides of the stack while the
stack yet is maintained under the squeezing-out pressure; subsequently re-applying the high pressure by the application of permanent clamping means; and subsequently while
10 the stack is under the high compression of the latter and while the marginal detergent is soft, applying a vacuum around the stack thereby removing air from the soft marginal detergent; and subsequently, while the stack
15 is maintained under the high compression of said permanent clamping means forming a thick embedment around the stack and permanent clamping means, of material similar to said dielectric detergent, while the stack
20 yet is surrounded by the vacuum, thereby keeping from the embedment any air or moisture squeezed out of the stack and entrained in the marginal detergent, and forming a thick insulating seal around the margins of
25 the sheets and the sides of the stack.
26. The method of making an electrical condenser of a stack of metal armature sheets and non-porous dielectric sheets which consists in first removing air and moisture from
30 the surfaces of the sheets in the stack by squeezing out a normally solid dielectric detergent in molten condition from between the sheets; subsequently placing such stack with cleansed sheet-surfaces in clamping means
35 which holds the sheets in the intimate surface contact with one another which is permitted by said cleansing of air and moisture; and subsequently placing such cleansed and clamped stack in condition for service by immersing it and its clamping means in an insulating liquid.
27. A series-sectional high potential mica sheet condenser comprising a stack of foil sheets alternating with the micas, the surfaces 45
of the sheets in the stack being freed of air and moisture; a metal casing enclosing the stack and connected thereto as a condenser terminal; high pressure clamping means holding the stack sheets in the casing in the
50 intimate surface contact which is permitted by the freedom of the stack sheets from air and moisture; and a filling embedment of solid insulating material, liquid at high condenser operating temperatures and occupying a substantially thick space inside the casing and around the stack and the high pressure clamping means, and insulating the higher potential portions of the stack from the casing as a condenser terminal.
- 55 28. An electrical condenser comprising a stack of metal armature sheets and non-porous dielectric sheets, the surfaces of the sheets in the stack being freed of air and moisture and in the intimate surface contact with one another permitted by absence of air and moisture; a casing for said stack and so proportioned thereto as to provide a space of substantial thickness between the higher potential portions of the stack and the walls of the casing; a stack embedment filling in said space and consisting of a dielectric material which is normally solid but fusible at high operating temperatures of the condenser; and means maintaining sufficiently high mechanical compression on the ends of the stack 70
in the casing to maintain the stack sheets, when said embedment is in fused condition, in their said permissively intimate surface contact relations and thereby prevent flow between the sheets of the embedment and any air or moisture; said compression means also being embedded in said dielectric filling.
29. The method of making an electrical condenser of a stack of metal armature sheets and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression until the squeezed-out detergent congeals 85
at the margins of the sheets and sides of the stack and seals the stack against re-entrance of air and moisture between its sheets; and subsequently placing such stack in an enclosing casing and applying service clamping means to its ends, and embedding the stack in normally solid dielectric material in molten condition in the casing and surrounding the stack in a substantially thick mass which melts the marginal detergent and upon itself 90
congealing seals the margins of adjacent stack sheets; said clamping means also being embedded in said dielectric material and exerting sufficient compression on the stack ends to maintain the sheets in their said permissible cleansed and intimate surface contact condition whenever the sealing embedding material is in a fused state.
30. An electrical condenser comprising a stack of metal armature sheets and of non-porous dielectric sheets, the surfaces of the sheets in the stack being freed of air and moisture and in the intimate surface contact with one another which is permitted by such freedom of air and moisture; a casing enclosing said stack and so proportioned thereto as to provide a space between the stack and the walls of the casing; and a stack embedment filling in said space and consisting of a solid dielectric material surrounding the sides of the stack in a substantially thick mass and sealing the margins of the stack sheets against entrance of air and moisture and holding said sheets in their intimate surface contact relations.

31. The method of making an electrical condenser of a stack of metal armature sheets and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression until the squeezed-out detergent congeals at the margins of the sheets and sides of the stack and seals the stack against re-entrance of air and moisture between its sheets; and subsequently placing such stack in an enclosing casing proportioned thereto to provide a substantially thick space between the stack and the walls of the casing and inserting in said space a filler of dielectric material similar to said detergent surrounding the sides of the stack therewith and thereby melting the marginal detergent but continuing the sealing of the margins of the stack sheets against re-entrance of air and moisture between them and holding said sheets in their said intimate surface contact condition.
32. An electrical condenser comprising a stack of metal armature sheets and non-porous dielectric sheets, the surfaces of the sheets in the stack being freed of air and moisture and in the intimate surface contact with one another which is permitted by such freedom of air and moisture; an embedment for such stack consisting of a substantially thick mass of normally solid dielectric material which is fusible at high operating temperatures of the condenser and which surrounds the sides of the stack and seals the margins of the stack sheets; and high pressure clamping means also embedded in said dielectric material and cooperating therewith in maintaining the intimate surface contact relations of the stack sheets and preventing re-entrance of air and moisture between them.
33. The method of making an electrical condenser of a stack of metal armature sheets and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression until the squeezed-out detergent congeals at the margins of the sheets and sides of the stack and seals the stack against re-entrance of air and moisture between its sheets; and subsequently applying permanent clamping means to the ends of the stack and embedding both the stack and the clamping means in normally solid dielectric material in molten condition surrounding the stack in a substantially thick mass which melts the marginal detergent and upon its own congealing seals the margins of adjacent stack sheets, 70 said clamping means exerting sufficient compression on the stack ends to maintain the stack sheets in their cleansed and intimate surface contact conditions while the sealing embedding material is in a molten state. 75
34. An electrical condenser comprising a stack of metal armature sheets and non-porous dielectric sheets, the surfaces of the sheets in the stack being freed of air and moisture and in the intimate surface contact 80 which is permitted by such freedom of air and moisture; and an embedment for such stack consisting of substantially thick mass of solid dielectric material surrounding the sides of the stack, sealing the margins of the 85 stack sheets against re-entrance of air and moisture, and holding said sheets in their intimate surface contact relations.
35. The method of making an electrical condenser of a stack of metal armature sheets 90 and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression 95 until the squeezed-out detergent congeals at the margins of the sheets and sides of the stack and seals the stack against re-entrance of air and moisture between its sheets; and subsequently embedding such stack in normally 100 solid dielectric material surrounding the stack in a molten state in a substantially thick mass which melts the marginal detergent but continues the sealing of the margins of the 105 adjacent stack sheets and maintains them in 110 their cleansed and intimate surface contact conditions.
36. An electrical condenser comprising a stack of metal armature sheets and non-porous dielectric sheets, the surfaces of the dielectric sheets being freed of air and moisture and in the intimate surface contact with one another which is permitted by such freedom of air and moisture, the margins of the stack being sealed by a normally solid dielectric material which is fusible at high service temperatures of the condenser; and a permanent metal service clamp applied on the ends of the stack and exerting sufficient mechanical compression on the stack to maintain said 120 cleansed and intimate surface contact conditions of the stack sheets upon fusing of said dielectric sealing material. 125
37. The method of making an electric condenser of a stack of metal armature sheets 130

and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression until the squeezed-out detergent congeals at the margins of the sheets and sides of the stack and seals the stack against re-entrance of air and moisture between its sheets; and subsequently applying to the ends of such stack permanent-service clamping means exerting sufficient compression on the stack ends to maintain such cleansed and intimate surface contact conditions of the stack sheets upon fusing of the sealing dielectric material.

38. An electrical condenser comprising a stack of metal armature sheets and of non-porous dielectric sheets the surfaces of the sheets in the stack being freed of air and moisture and in the intimate surface contact condition permitted by such freedom of air and moisture; a condenser casing enclosing said stack; and high pressure clamping means applied on the ends of the stack and maintain-

ing the sheets of the enclosed stack in their intimate surface contact relations and preventing access of air and moisture to their surfaces.

39. The method of making an electrical condenser of a stack of metal armature sheets and non-porous dielectric sheets, which consists in subjecting said stack, while its sheets are separated by a normally solid dielectric detergent in molten condition, to a mechanical compression on its ends which is sufficiently high to squeeze out the detergent and air and moisture entrained therein and to force the cleansed sheets in the intimate surface contact permitted by such cleansing of air and moisture; maintaining such compression until the squeezed-out detergent congeals at the margins of the sheets and sides of the stack and seals the stack against re-entrance of air and moisture between its sheets; and subsequently enclosing such stack in a permanent casing under mechanical compression sufficiently high to maintain the sheets of the enclosed stack in their cleansed and intimate surface contact conditions during service even upon fusing of said sealing dielectric by service temperatures.

GREENLEAF WHITTIER PICKARD.
